DESIGN FOR A SHOE SOLE

Paul Van Cleef, Chicago, Ill., assignor to Van Cleef Bros., Chicago, Ill., a partnership consisting of Noah Van Cleef, Felix Van Cleef, Maxime Van Cleef, and Paul Van Cleef

Application May 22, 1933. Serial No. 48,182

Term of patent 7 years

To all whom it may concern:

Be it known that I, PAUL VAN CLEEF, a citizen of the United States, residing at Chicago, in the county of Cook and State of Illinois, have invented a new, original, and ornamental Design for Shoe Soles, of which the following is a specification, reference being had to the accompanying drawing forming a part thereof.

Figure 1 of the drawing is a face view of a shoe sole embodying the new design; and Figure 2 is a longitudinal section on the line 2—2 of Figure 1.

I claim:

The ornamental design for a shoe sole substantially as shown.

PAUL VAN CLEEF.
